APPARATUS FOR DEWAXING OIL

Harmon F. Fisher, Los Angeles, Calif., assignor to
 Union Oil Company of California, Los Angeles,
 Calif., a corporation of California

Application September 18, 1933, Serial No. 689,984

6 Claims. (Cl. 204—24)

The present invention relates to the separation of wax from wax-bearing oils and more particularly it pertains to the separation of a wax precipitate from a suspension thereof in oil.

8 In view of the presence of paraffine or of wax in a number of lubricating oil fractions derived from paraffine base crude oils, asphalt base crude oils or mixtures or blends thereof, and in view of the doubtful lubricating value of such paraffine 10 or wax, it has become customary, in the production of lubricating oils from petroleum fractions containing wax or paraffine, to remove most or a substantial portion of the wax or paraffine present in oil mainly for the purpose of lowering its 15 "pour point", and the temperature at which the oil congeals.

Recently a method has been developed for separating electrically the wax which has been precipitated from a wax-containing oil. According 20 to this method the wax-containing oil or a fraction thereof is first diluted with a light hydrocarbon fraction, such as naphtha, liquid propane, etc., then chilled to the proper temperature at which the wax precipitation takes place, and 25 finally the mixture of oil, diluent and precipitated wax is subjected to an electric field or electric current to aid the separation and deposition of the wax from this mixture. The treatment of the wax-oil-diluent mixture according to this process 30 causes the wax to deposit on the electrodes. In the case of some waxes, i. e., waxes which are apparently charged negatively, the deposition occurs on the positive electrodes since the wax particles subjected to an electric field appear to be 35 drawn to the electrode having a polarity opposite to that of the particles themselves. Therefore, if the wax is charged positively the above described electric treatment causes it to deposit on the negative electrode. However, some wax precipitates are found to be charged so that they 40 deposit on both the positive and the negative electrodes.

In operating according to the above described method it has been found that the potential gradient of the electric field must be comparatively high. Thus potential gradients of from 45 5,000 to 60,000 volts per inch of either continuous or interrupted direct current through the solution have been found to be effective in agglomerating and depositing the precipitated wax. Also, it has been discovered that time is an essential 50 element. Thus, it is necessary to maintain the mixture within the electric field for a certain period of time to cause the proper agglomeration 55 and deposition of the wax contained in the oil-

diluent solution. In view of the above described necessity of using electric fields of high intensity it has been customary to construct electric treaters so that the electric field, i. e., the gap between the positive and negative electrodes is comparatively short. With such small gaps it is obvious that the depositing of the wax on either or both electrodes will gradually diminish the space provided for the passage of the wax-containing mixture and finally completely close the gaps. Obviously, such gradual diminishing of the gap changes the velocity of the mixture passing therethrough, thereby changing the above described time element and causing an insufficient or incomplete depositing of the wax, so that the oil solution removed from such treaters may still contain considerable quantities of precipitated wax. The presence of such precipitated wax obviously raises the pour point of the final product and decreases the lubricating value of the oil.

It is, therefore, one of the objects of the present invention to obviate the above described defects and to provide for passing the wax-containing chilled oil solution continuously through an electric field and for simultaneously and continuously removing and withdrawing from this field the wax depositing on the electrodes.

It is a still further object of the present invention to provide a structure wherein the rate of passage of the oil containing the wax precipitate through an electric field may be maintained constant.

The above and other objects may be attained by continuously removing the deposited wax from the electrodes and allowing the thus removed wax to settle out more rapidly to the bottom of the treater from whence it is removed. The scrapers may also act as baffling means to cause the wax and oil mixture to pass through the electric field and to prevent its passage through the treater in a manner as to avoid complete treatment.

Now, therefore, broadly stated the invention resides in passing the chilled mixture of oil and wax through an electric field of a sufficiently high intensity and at a proper rate to cause the wax contained therein to deposit on certain of the electrodes, and to remove the thus deposited wax continuously for the purpose of maintaining the electric gap constant, thus permitting a sufficient period of treatment for the oil being dewaxed. The invention further resides in a dewaxing structure wherein the electrodes are of the plate or disk type and are arranged to alternate in polarity to produce an electric field be-

tween each pair of electrodes, and wherein certain of the electrodes are rotated and are provided with scraping means to remove from these rotating circular or disk electrodes any wax deposit formed thereon from the wax-bearing oil passing through the electric fields between said electrodes.

In its preferred form the invention comprises an electric treater, a plurality of stationary plate electrodes disposed therein, a plurality of circular electrodes of a polarity opposite to that of the stationary electrodes disposed within the treater, interspaced between the stationary electrodes and electrically insulated therefrom, means for rotating the circular electrodes, and scraping means to remove the wax depositing on the rotating electrodes by the wax-bearing oil passing between the electrodes, the deposit being caused by an electric field impressed between each pair of electrodes. The scraping means may also act as a baffle to force the oil and wax mixture to be treated to flow through the electric fields. The above described structure is also provided with an inlet for the introduction into the treater of the wax-bearing oil-solvent mixture, an outlet for the dewaxed oil-solvent mixture, and means, such as a screw pump, to remove from the treater the deposited wax which has been removed from the electrodes by the above described scraping means.

Other objects, advantages and features of the invention will be evident hereafter, and more particularly by reference to the accompanying drawing wherein:

Fig. 1 shows diagrammatically a vertical section through one embodiment of the present invention; and

Fig. 2 is a section along line A—A of Fig. 1.

Referring to the drawing, the treating chamber 10 is preferably cylindrical in form and is arranged so that its main axis is in the horizontal plane. End walls 11 and 12 enclose the treater, the latter being also provided with an inlet pipe 13 and an outlet pipe 14. The treater is further provided at its upper end with a hollow projection 15 closed at its top by a cover 16, while at its bottom the treater is provided with a similar projection 17 closed by plate 18 and provided at its side with a pipe 19. This pipe 19 encloses a screw pump 20 set on shaft 21. Pipe 19 is closed at its outer end by a plate 22 through which the shaft 21 passes through a stuffing box 23. Pipe 19 is also equipped with a wax discharge line 25.

Pipe 15 contains a supporting insulator 26 held in place by means of a plate 27 rigidly attached to and made integral with projection 15. The electrode 26 supports a plurality of stationary diaphragm electrodes 28 suspended therefrom within the treating chamber 10. These electrodes are in the form of segments of a circle and are cut out as at 29 for the passage of a shaft 30 described hereinbelow. This shaft 30 is disposed along the main axis of the treating chamber 10 and passes out through the respective walls 11 and 12 thereof through stuffing boxes 31 and 32, respectively. The latter also act as bearings for said shaft. A plurality of circular plate electrodes 33 are attached rigidly to shaft 30 and are disposed thereon in a manner so that they pass through the spaces between the stationary electrodes 28 and provide gaps or spaces 34 between said stationary and circular electrodes. An electric field of the desired intensity is impressed across these gaps 34 by connecting the stationary electrodes through the medium of wire 35 to a

source of an electric potential. This wire leads into the treating chamber 10 through an insulated inlet bushing 36. The circular plate electrodes 33 are grounded through shaft 30 and the body of the structure, and the return circuit to the electric potential source is completed through the ground. A plurality of scraping plates or diaphragms 37 are attached at their lower ends to plate 18. These plates project upwardly through pipe 17 and abut with their edges 38 against the surfaces of the circular plate electrodes 33. Alternatively, one slotted scraping plate may be used, permitting passage of the plate electrodes 33.

In operation, the diluted waxy oil chilled to a temperature at which the desired wax has precipitated out of solution, is passed into the treating chamber 10 through inlet 13. Due to the positioning of the scraper diaphragm 37, which closes the space between the electrodes 33 below shaft 30, the wax and oil mixture passes through the gaps or spaces 34 between the interspaced electrodes 28 and 33. Simultaneously with this introduction of the oil, an electric field of the desired intensity is maintained across the gaps 34 by impressing an electric potential of the desired intensity between wire 35 and the ground. The action of the electric field on the oil-wax mixture passing through the gaps 34 is such that the wax is deposited on the surfaces of certain of the electrodes. The polarities of the electrodes must be selected so that the wax is deposited on the circular plate electrodes 33 attached to the shaft 30. The thus dewaxed oil solution passes out of the treating chamber 10 through outlet pipe 14.

As stated above the proper dewaxing of a wax-bearing oil requires a certain potential gradient across the electric field through which the wax and oil mixture pass as well as a certain and definite period of time of treatment. Obviously the deposition of the wax on the electrodes 33 decreases the gaps 34, thus increasing the velocity of the oil passing through the electric field and preventing a proper dewaxing of the oil. To obviate this disadvantage the circular electrodes 33 attached to shaft 30 are rotated by actuating said shaft. This rotation of the circular electrodes 33 causes the scraper diaphragms 37, abutting against the surfaces of these electrodes by means of their edges 38, to remove from these electrodes the wax deposited thereon. Such a removal of the deposited wax obviously permits the maintenance of constant gaps or spaces between the electrodes 28 and 33, thus allowing the oil-wax mixture (introduced into the treater at a predetermined and constant rate) the period of time necessary for a proper deposition of the wax. The wax scraped off the faces or surfaces of the electrodes 33 by the scrapers 37 falls down into pipe 17 and is removed therefrom through pipes 19 and 25 by the actuation of the screw 20 rotated by the shaft 21.

The direction of rotation of the plate electrodes 33 may be such that it is either in the direction of flow of the oil being dewaxed, or it may be countercurrent to such oil flow. However, a countercurrent rotation is preferred if it is desired to provide the cleanest electrode surfaces to or at the finishing stages of the treatment.

It is to be understood that the above disclosures are not to be construed as limiting but merely as descriptive of the generic invention, since many variations may be made by those skilled in the art within the scope of the appended claims.

I claim:

1. An apparatus for dewaxing wax-bearing oil comprising a chamber, a stationary electrode disposed within said chamber, a movable plate electrode within said chamber adjacent said stationary electrode but without contact therewith, means in engagement with said plate electrode adapted to move the same, means in communication with said chamber to pass wax-bearing oil between said stationary and movable electrodes, means in electrical contact with said electrodes adapted to impress an electric field on the oil and to cause depositing of wax therefrom, and scraping means in engagement with said movable electrode to remove the wax deposited thereon.
- 5 2. An apparatus as in claim 1 wherein said plate electrode is a rotatable disc electrode.
- 10 3. An apparatus for dewaxing wax-bearing oil comprising a chamber, stationary plate electrodes disposed within said chamber, movable plate electrodes within said chamber between each pair of said stationary electrodes but without contact therewith, means in engagement with said plate electrodes adapted to move the same, means in communication with said chamber to pass wax-bearing oil between said stationary and movable electrodes, means in electrical contact with
- 15 4. An apparatus as in claim 1 in which the scraping means is a slotted scraper.
- 20 5. An apparatus for dewaxing wax-bearing oil comprising a chamber, a stationary electrode disposed within said chamber, said stationary electrode being in the form of a segment of a circle, a movable plate electrode within said chamber adjacent said stationary electrode but without contact therewith, means in engagement with said plate electrode adapted to move the same, means in communication with said chamber to pass wax-bearing oil between said stationary and movable electrodes, means in electrical contact with said electrodes adapted to impress an electric field on the oil and to cause depositing of wax therefrom, and scraping means in engagement with said movable electrode to remove the wax deposited thereon.
- 25 6. An apparatus as in claim 5 wherein said stationary electrode is substantially U-shaped.
